PYROTECHNIC DEVICE

Louis F. Fieser, Belmont, Mass., and William F. Van Loenen, Los Altos, Calif.; said Fieser assignor to the United States of America, and said Van Loenen assignor to Kaiser Aluminum & Chemical Corporation, a corporation of Delaware

Application January 4, 1946, Serial No. 639,068

13 Claims. (Cl. 102--7)

1

The present invention relates to a package or container for incendiary material, and more particularly to a floatable package containing incendiary material and adapted for aquatic fireworks displays, signal flares and the like.

In the copending application of Van Loenen, Serial No. 492,989, filed July 1, 1943, now Patent No. 2,509,710, dated May 30, 1950, there is set forth the production of magnesium metal from magnesium oxide by carbothermic reduction according to the process disclosed in Patent No. 1,884,993 (Hansgirg). Therein a mixture of magnesium oxide and carbon is converted into magnesium vapor and carbon monoxide by the heat of an electric arc furnace. This gaseous mixture is discharged from the region of the arc at a high enough temperature (above 1800° C.) that reversal of the reaction does not occur, and is then suddenly cooled and diluted by injecting large volumes of a shock chilling agent, which may be hydrogen, natural gas, hydrocarbon vapor or even a spray of liquid hydrocarbon.

In one particular practice of the process natural gas is employed. The magnesium vapor is condensed to magnesium metal in the form of extremely fine dust. Some of the vapor recombines with carbon monoxide with the result that the solid material precipitated in the condensing chamber comprises a substantial proportion from 30 to 60% of magnesium dust with the remaining 70 to 40% comprising carbon, magnesium oxide and other impurities. A typical sample of a normal run shows 47% by weight of magnesium metal dust.

This condensate, i. e., the magnesium dust with admixed impurities, while it requires coalescing of the magnesium dust to produce compact metal, is, nevertheless, highly pyrophoric, and will combust spontaneously when exposed to the atmosphere. To diminish this tendency so that the material may be safely handled for sublimation into crystalline magnesium metal, it is now customary to wet the precipitate with a light hydrocarbon oil having a flash point above 100° F., with or without the addition of asphalt to produce a relatively stiff plastic mass which is termed herein carbothermic magnesium paste. The asphalt is added when it is desired to make the mass somewhat cohesive, particularly where it

is desired to tablet the material into compact pellets or briquettes. Where the shock chilling is produced by oil spray, the shock chilling oil wets the precipitate and inhibits ignition while forming carbothermic magnesium paste.

Experiments proved that this carbothermic magnesium paste, i. e., magnesium dust and impurities wet with oil and with or without asphalt or other binder is not spontaneously reactive with dry air. However, water vapor or spray will ignite the carbothermic magnesium paste and this paste-water combination provides an inexpensive incendiary.

The average analysis of the magnesium dust is:

	Per Cent
Magnesium	50
Carbon	19
Inert (principally MgO)	31

20 A small percentage of the magnesium (approximately 5%) exists as one or both of the carbides— MgC_2 and Mg_2C_3 . There is generally a trace of sodium which is believed to be in elemental form and possibly minor traces of other carbides such as calcium, silicon and aluminum originating from the ash constituents from the metallurgical coke in the reduction furnace and/or from the minor ash constituent in the petroleum coke used for reduction. With the exception of occasional carry over of particles from the reduction furnace all of these materials have an ultimate particle size below the resolving power of optical microscopes. Electron microphotographs reveal agglomerates several microns in diameter and ultimate particles in the neighborhood of 0.1 micron.

40 The hydrocarbons which may be employed for wetting the magnesium dust may advantageously consist of a mixture of distillate and asphalt, in which the proportions of distillate may vary from about 70% to about 95% by weight and the asphalt, from about 30% to about 5% by weight. Typical analyses of the components of the mixture which have proved successful are as follows:

	<i>Distillate</i>
Gravity °API at 60° F.	23
Flash point Pensky-Marten closed cup °F.	180
Viscosity Sayboldt seconds Universal at 50 100° F.	60

Orcutt-120 asphalt

Gravity °API at 60° F----- 10.2
 Flash point Pensky-Marten closed cup °F--- 430
 Viscosity Sayboldt seconds Furol at 210° F--- 145

To produce a mixture of crude dust and hydrocarbons, safe for shipment and suitable for compounding incendiary fuels, the shock chilled dust is conveyed in a closed atmosphere under natural gas to pug mill type extrusion presses where it is thoroughly mixed with the desired hydrocarbons and extruded through a die plate into open drums. The limitations on this equipment are such that practical concentrations can be made between 55% and 70% solids, the balance hydrocarbons. For reasons of safety it is undesirable to include low flash hydrocarbons at this stage. Various mixtures of fuel oils, or asphalt cut-back with fuel oils, or kerosenes in a considerable range, are practical from a production standpoint. This magnesium material when thoroughly wetted with hydrocarbons is not easily ignited nor will it flash or explode. However, if allowed to air dry or come in contact with water, acid, or perspiration, it will sooner or later ignite when such liquid has cut through the protective layer of hydrocarbon so as to react with the finely divided magnesium.

The construction of well known incendiaries, particularly those of the known "stick" form, involves the use of cast solid magnesium metal which is difficult to ignite except by thermite or a similar igniting charge. Incendiaries and flares of magnesium powder have therefore been made by first producing magnesium in solid metal form and then subdividing it. By the method of this invention the raw powder coming from the shock chilling step of the carbothermic process may be directly substituted for the far more expensive method at present utilized. Also, the magnesium metal as employed in the carbothermic magnesium paste is of a state of subdivision far greater than that which it is practicable to produce by mechanical comminution.

In the present invention the magnesium powder even in the impure form as recovered from the vapor produced by carbothermic reduction, and with or without other materials, may be directly applied to incendiary use without going through the stage of first producing the coalesced or solid metal. A great advantage of using such a finely divided metal is that the desired ignition may be secured from mere contact with such simple media as air and water. Any substance which gives up oxygen freely enough to produce ignition, i. e., rapid combustion, may be used.

The finely divided magnesium produced in the carbothermic process has a particle size of substantially less than one micron, and as heretofore stated is capable of spontaneous combustion with the atmosphere unless wetted down with a material such as hydrocarbon oil. It is obvious that a particle size on the order of that mentioned cannot be achieved on a commercial scale by use of mechanical means. The fine particles, because of their pyrophoric qualities, would present a considerable fire hazard if mechanically produced, and the high cost and complicated equipment necessary to mechanically produce such particles in an inert atmosphere would be impractical. Thus additional advantages of this invention are that it utilizes an incendiary material of finely divided magnesium of a particle size never before attainable on a commercial scale, and yet such finely divided magnesium is

capable of rapid and economic production, and can be safely handled.

The carbothermic magnesium paste may be used as is, as a paste, or it may consist of compacted or tableted pellets or briquettes. Magnesium and/or aluminum in the form of solid metal including alloys thereof, either as a part or all of the container, or an admix in the form of borings, turnings, screenings, or pieces of scrap metal, may be used in conjunction with the carbothermic magnesium paste and may partake of the incendiary reaction, after the same is initiated.

It is to be understood that after the carbothermic magnesium paste is once ignited, it will continue to burn by reaction with the oxygen and/or nitrogen of the air, and tends by the heat and flame produced to ignite adjacent combustibles. Water applied to extinguish it is of no use as it reacts readily with the magnesium, accelerating combustion. Such common extinguishers as carbon dioxide actually accelerate combustion.

Additional reagents which tend to sustain combustion of the magnesium powder, such as ferric oxide, barium oxide and other similar metal oxides, potassium chlorate, sodium nitrate, and other similar metallic salts containing combined oxygen, sulfur, gasoline or carbon, and mixtures thereof, may be added to the carbothermic magnesium paste, and after ignition is instituted as by the liquid oxidizing agent, the further combustion may be sustained or aided by such reagents. Where a liquid, such as water, is employed to produce ignition, the resulting gas, such as hydrogen, is combustible and tends to spread the fire. Similarly, liquids which by deoxidation by the finely divided magnesium produce combustible gases, tend also to spread the fire by producing a flame reaching into adjacent space for oxygen to support its combustion.

While plain water is the simplest liquid oxidizing agent, there may be situations or conditions of use calling for the addition of antifreeze agents or of liquids which will withstand low temperatures without solidification. Thus alcohols, such as methanol, aldehydes and organic acids may be employed. Also inorganic compounds such as chlorates, permanganates, particularly of the alkali metals, may be dissolved in the liquid or associated therewith. Wetting agents to accelerate the wetting of the incendiary material with the liquid may be used. The employment of such agents is shown in the co-pending application of Van Loenen, Serial Number 555,766, filed September 25, 1944.

If it is desired to ignite the magnesium powder in a body of water, or under similar conditions, particularly where it is desired to create a flare on a body of water, it is advantageous to add an agent which will cause heat and/or gas generation, such as quicklime and/or carbides. The addition of carbides to the finely divided magnesium powder is particularly advantageous due to their gas generating properties, because the pressure generated causes the flame to shoot out more rapidly than under condition wherein the incendiary material does not contain carbides.

The primary object of the present invention is to form a container for an incendiary material constructed to bring water, or other oxidizing liquid, into reaction to create incendiary conditions.

Another object is to provide a floatable aquatic fireworks device comprising any incendiary ma-

terial which ignites when reacting with water, and particularly a magnesium incendiary such as a carbothermic paste-carbide mixture, or a carbothermic dust mixture with hydrocarbon which has been destructively distilled to give a coked mass having discrete magnesium particles therein, or compacted masses such as pellets of carbothermic dust.

A further object is to provide a floatable explosive device for fireworks displays.

Another object is to provide a container for an incendiary charge including pyrophoric magnesium as an ingredient, and being provided with at least one opening adapted to admit an oxidizing liquid, such as water, for reaction with the charge.

Other and further objects and advantages of this invention will be apparent from the following description and from the appended claims.

The accompanying drawings illustrate various embodiments of this invention. In the drawings:

Figure 1 is a longitudinal vertical section of a floatable incendiary device embodying features of this invention;

Figure 2 is a perspective view of triangular package embodying certain features of the invention and

Figure 3 is a perspective view of the device of Figure 2 with cut-away portion showing the filling elements;

Figure 4 is a vertical perspective view of still another embodiment of the invention, with cut-away portion showing the filling features of this embodiment and

Figure 5 is an end view of the device of Figure 4 showing an igniting means.

Figure 6 is a vertical sectional view of the central portion of the embodiment of Figure 4.

Referring to Figure 1 of the drawing particularly, the numeral 10 generally represents a floatable incendiary device and embodies the features of the invention. The bomb 10 comprises a waxed carton 11, about the size of a milk carton, and square in cross-section. The carton 11 comprises top wall 12, bottom wall 13, and four side walls, each of which is represented by the numeral 14.

The top wall 12 is provided with a suitable flap opening 15 which is adapted to open and close and is employed to introduce the incendiary mix 16 into carton 11. Flap opening 15 may be sealed after a suitable quantity of charge 16 is introduced into carton 11. The carton 11 is usually filled with charge 16 in sufficient amount to submerge 75-80% thereof in water W.

The top wall 12 is substantially centrally provided with an aperture 17. Side walls 14 are provided with two apertures or holes 18 and 19. Hole 18 is disposed in one of side walls 14 adjacent the top wall 12, while hole 19 is disposed in one of side walls 14 adjacent the bottom 13. The holes 18 and 19 may both be disposed in the same one of said side walls 14 or in different walls as desired.

The bottom wall 13 is substantially centrally provided with an aperture 20. An inner lining of absorbent paper 21, or other water absorbent material is disposed in carton 11. The lining 21 serves as a wick to more readily bring water into reactive contact with charge 16 through the openings in carton 11.

The carton 11 may be of any desired size or shape. The openings 17, 18, 19 and 20 may vary in size. E. g., said openings may have a diameter

ranging from one-eighth of an inch to one-half inch. The smaller the opening, the more time it takes to bring sufficient water into reactive contact with charge 16 to cause ignition. While carton 11 is preferably made of paper, cardboard, or the like, any other material may be employed, and preferably one which will add buoyancy.

In operation, the incendiary device 10 may be dropped from an airplane, or is otherwise thrown into water. The device 10 rights itself in the water, either end up, and water begins to seep through the openings in carton 11 which are under the surface of the water. The entrance of the water into contact with charge 16 through the appropriate openings is aided by the water absorbent lining 21 which by capillary action bring water into contact with an increased area of the charge 16 to promote reaction.

After sufficient water is in contact with charge 16 an oxidation reduction reaction occurs with sufficient rapidity to cause ignition thereof and sufficient pressure is built up within carton 11 to cause a flame to shoot out of the openings above the water, and this flame may be of various colors depending upon the charge components, as further explained below. If desired, the openings 17 and 20 in the top and bottom walls respectively of carton 11 may be much smaller in diameter or area than openings 18 and 19 in side walls 14. In this way, the flame more predominately shoots out the side opening above water level.

The charge 16 may take the form of small particles, of indiscriminate size, and comprising pelletized or briquetted carbothermic magnesium dust, with or without added hydrocarbon and with or without added carbide. For example, a carbothermic magnesium paste mixture may be pressed to give pellets which are useful as charge.

Alternatively, a carbothermic magnesium dust-hydrocarbon mixture may be formed into suitably sized pellets. These pellets are dried at a temperature below the coking temperature of the hydrocarbon and then coked at a temperature between 800-900° F. The coked mass formed has discrete particles of magnesium dispersed therein. The coked incendiary pellet is very reactive with water and ignites easily. When carbide is present it forms acetylene in contact with water, in addition to the hydrogen generated from the magnesium in the carbothermic paste.

The device 10 is somewhat limited as to the quantity of charge 16 employed therein so as to maintain its floating characteristics. The quantity of charge 16 is usually present in an amount by weight so that the incendiary 10 is 75-80% submerged in water, and the opening 18 or 19 if the device rights other way up, is above the water level so that a flame initially shoots out over the water.

Device 10 usually does not immediately ignite as it requires a certain period of time to bring sufficient water into reactive contact with charge 16. It is known as a "sleeper" and the periods of dormancy will vary with such factors as the size of the water admitting opening, and the form or shape of the particles of charge 16.

Figures 2 and 3 show an incendiary device of triangular cross-section which comprises side-walls 30, all being suitably of the same dimensions, and end flaps 31, which fold over on each other and are sealed suitably by application of adhesive to the joining surfaces, and end flaps 32 which contain concentric apertures 33 which register with each other when the flaps are fold-

ed upon each other to close the device. The aperture in the flap which is in the outermost location when the device is closed is sealed by sealing tab 34, suitably of metal such as copper although it may be of any other desired material, which tab is pulled off when the device is placed in operation. It has been found advantageous to dispose reinforcing rings 35 about apertures 33 to prevent tearing along undesired lines.

In Figure 3, the sealing tab 34 is shown after detachment, as when the device is to be thrown into or placed in water. In this view also are shown the interior features of this particular embodiment. The outer walls and flaps of the device are conveniently made of cardboard, although any other material which is floatable in this construction will serve. Adjacent the inner surfaces of sidewalls 30 is a liner of asbestos 36 which protects the sidewalls during combustion and directs the flame out the end sections and increases its concentration thereby. Disposed within the asbestos liner is a second liner 37 of corrugated cardboard which acts as a reinforcer and also serves to keep the oily incendiary mix or gel out of contact with the asbestos. Within the liner 37 is charged incendiary composition 38 which in this particular embodiment comprises an intimate mixture of 15% by weight of iron oxide (mill scale) which is ground to pass through an 80-mesh screen and which contains at least 65% iron, and 85% by weight of carbothermic magnesium paste which has been obtained as described above and then dried to about 85% solids, about 3.5% asphalt and about 11.5% Stoddard solvent. The dried carbothermic paste passes a 6-mesh screen and contains at least 40% metallic magnesium.

At the end of the device adjacent the apertures 33 in contact with the innermost aperture 33 is a gas-generating device 39 comprising an amount of a material, such as calcium carbide, which generates gas upon contact with water, enclosed in a suitable container which is of material that is permeable to water or other oxidizing liquid. The gas-generating device in this example comprises an amount of calcium carbide enclosed in a piece of cheesecloth lined with absorbent paper, the cheesecloth being drawn around the filling to form a bag, the stem of which is secured with 2 or 3 turns of lead wire 40. The generator device does not function in this invention to cause direct combustion, but rather may speed up the ignition of the incendiary charge somewhat inasmuch as the water passing through the igniter is warmed by the reaction of part of it with the carbide to form acetylene. The warmed water acts on the incendiary composition to cause combustion. An important function of the carbide in the element, which for convenience has been called the "generator," is to produce a combustible gas which causes long flames to shoot out across the water when the incendiary has been ignited, and another function is the production of heat.

Another embodiment of this invention is shown in Figures 4, 5 and 6. The device of this embodiment is a carton of rectangular cross-section, wherein there are 2 wider sidewalls 41 and 2 narrower sidewalls 42. The top and base of the carton are suitably closed by flaps, as 43, which, after the incendiary device is assembled, are sealed by adhesive applied to the contact faces thereof. Disposed within the carton adjacent to the wider sidewalls 41 only and co-extensive therewith are asbestos liners 44. Disposed within

the carton adjacent the narrower sidewalls 42 and, along the wider sidewalls, adjacent asbestos liners 44 is a reinforcing liner 45 of corrugated cardboard. In the center of one of the narrower sidewalls 42 is disposed an aperture 48 for the entrance of the oxidizing liquid, or water. This aperture is also suitably reinforced by cardboard ring 46 and sealed by sealing tear-tab 47, in this instance of copper although cardboard or other material or metal may be used. There is an aperture in corrugated liner 45 concentric with aperture 48 and registering therewith when the device is assembled. A corresponding aperture is disposed within the corrugated liner at the narrower sidewall opposite the water-entrance aperture and registers with an aperture 56 in this narrower sidewall, aperture 56 being sealed by combustible window 55. In the assembled device a gas-generator 39, similar to the one described in connection with Figures 2 and 3, is held against the water-entrance aperture 48 by one end of a tube 49, suitably of cardboard, which is of the same diameter as the aperture, and the other end of which tube abuts the aperture in the liner 45 at the sidewall opposite the water-entrance aperture. In this embodiment, the gas-generator may comprise calcium carbide enclosed in absorbent paper and without the cheesecloth covering. The ends of the bag are allowed to rest in the tube 49.

When the gas-generator and tube have been placed in the incendiary device, the incendiary mixture 50 is charged in and is of the same composition as described in the device of Figures 2 and 3.

On the narrower sidewall opposite the wall containing the water-entrance aperture is disposed another ignition device 51 which comprises a casing adapted to enclose a delayed-action igniting means of known composition not critical to this invention and a burning composition 53 consisting of potassium perchlorate, paraffin and charcoal. Device 51 is filled to the extent desired with the burning composition, a space being left for the delayed-action igniting means, the opening in the top of the device being sealed off by a rubber sealing compound, or other sealing composition, 52. When it is desired to activate the incendiary the delayed-action igniter 54 is inserted, through a hole dug through the composition 52, into device 51 and the incendiary or fireworks device is set in place. Device 51 is suitably of Celluloid and Celluloid window 55 is glued into aperture 56, as shown in Figure 6.

Device 51 is useful where it is desired to delay the ignition of the flare or display, as for instance after it has floated for considerable time and distance. The delayed-action igniter is activated in due time and causes the burning composition to take fire, thereby causing burning of the Celluloid window 55. The incendiary composition 50 may then be directly ignited, or water may enter aperture 56 and ignite the incendiary. In either case water comes into contact with the gas-generator and produces acetylene which enables the production of a long flame. The asbestos liners on the wider sidewalls, on one or the other of which the device floats, direct the flame out the narrower walls, increasing the concentration thereof.

Where cardboard, or similar material, is used in constructing the containers used in this incendiary device, it is advantageous to coat the cardboard or other material, on both the inner and outer surfaces of the container, with a water- and oil-proofing lacquer, such as Vinylite resin

lacquer. This protects against water-logging and against softening and deterioration of the container by absorption of oil from the hydrocarbon containing incendiary charge. It is also advantageous to dip the assembled device in liquefied thermoplastic coating wax, after which the coating is allowed to cool and harden prior to packing or storing of the device.

Although iron oxide has been shown as the solid oxidizing agent in the above examples, other oxidizing agents may be added as stated previously. It has been found particularly useful, for example, to add strontium nitrate in making red flares, barium nitrate in making green flares, etc. Other materials which produce colored flames are suitably added in the incendiary mixture, for instance, the chloride of strontium or barium, etc. It is believed, however, that iron oxide is an especially advantageous additive in that it facilitates dispersion of water through the incendiary mass. It is preferred to add not over about 15% by weight of oxidizing agent, although lesser amounts are useful in the composition of this invention.

While the above examples have been described with reference to cardboard carton containers, the container can also be made of metal, preferably lightweight metal, or other material. For instance, an ordinary can, such as a beer can, has formed the container and only such amount of composition has been charged in as will leave sufficient air space to insure buoyancy. The container can also have an aperture to permit entrance of water to the charge.

Any means may be employed to lend buoyancy to the floatable display device. Air tubes may be inserted within the container in contact with the charging composition. It is also intended to include buoyancy aids disposed outside of the charge-holding container and suitably secured or associated therewith. Vacuum tubes or balls may be employed where greater buoyancy is required.

The addition of a gas-generating agent, particularly calcium carbide, is not essential to the ignition of the charging composition, but especially in combination with an incendiary charge, is advantageous in producing long flames. The carbothermic magnesium paste can be added without drying. The carbide may be distributed through the paste instead of being held in a special container as described above. The percentages given in this specification and the appended claims are percentages by weight, of all constituents.

The drawings and above specific description have been given for purposes of illustration only, and variations and modifications may be made therein without departing from the spirit and scope of this invention as indicated by the appended claims.

What is claimed is:

1. A floatable incendiary comprising, a container provided with two spaced apart openings, one of said openings being adapted to admit water when the container is afloat and being disposed below water level, the other of said openings being adapted to eject a flame across the surface of the water and disposed in a side wall and above the water level when said container is afloat, pyrophoric magnesium obtained by shock-chilling magnesium-containing vapors and stabilized toward air disposed within the container

for reaction with the admitted water, and buoyancy means associated with said container.

2. A floatable incendiary comprising a buoyant container and a charge disposed therein comprising pyrophoric magnesium obtained by shock-chilling magnesium-containing vapors and having a protective coating of hydrocarbon and a solid oxidizing agent in the amount of not over about 15% by weight, said container having means to admit water into contact with said charge and having an aperture disposed in a side wall thereof and lying above the water level when said container is afloat and being adapted to direct flame horizontally across the surface of the water.

3. Incendiary as in claim 2 wherein the oxidizing agent is iron oxide.

4. Incendiary as in claim 2 wherein the oxidizing agent is strontium nitrate.

5. Incendiary as in claim 2 wherein the oxidizing agent is barium nitrate.

6. A floatable incendiary device comprising a cardboard carton of triangular cross-section, the ends of said carton being closed by sealed flaps, the flaps at one end being provided with registering apertures, the outermost aperture being sealed by a removable metal closure tab, an amount of material adapted to generate combustible gas upon reaction with water disposed in a water-permeable container within said carton adjacent said apertures, an asbestos lining disposed within said carton adjacent the sidewalls thereof, a corrugated cardboard lining disposed within said carton adjacent said asbestos lining, and disposed within said lined carton an incendiary charge comprising pyrophoric magnesium, a protective amount of hydrocarbon and a solid oxidizing agent.

7. Device as in claim 6 wherein the solid oxidizing agent is iron oxide.

8. Device as in claim 6 wherein the gas-generating material is calcium carbide.

9. A floatable incendiary device comprising a sealed cardboard carton of rectangular cross-section, said carton having two wider and two narrower sidewalls, one of said narrower sidewalls having an aperture therein, a removable tab sealing said aperture, the second narrower sidewall having an aperture opposite said first-mentioned aperture, said second-mentioned aperture being sealed with a combustible tab, an asbestos liner disposed adjacent each of said wider sidewalls, a corrugated liner disposed within said asbestos liner and also adjacent said narrower sidewalls and having apertures registering with said first and second apertures, a cardboard tube abutting at one end said second aperture in said corrugated liner, a water-permeable container containing a substance adapted to generate combustible gas upon reaction with water disposed between the other end of said tube and said first-mentioned aperture, and disposed within said lined container an incendiary charge comprising pyrophoric magnesium, a protective amount of hydrocarbon and a solid oxidizing agent.

10. Incendiary device as in claim 9 having secured to said second narrower sidewall a delayed-ignition device.

11. A floatable fireworks device comprising a container and disposed therein a charge of magnesium obtained by shock-chilling magnesium-containing vapors and stabilized toward air, said container having at least one aperture disposed above the water level when afloat and adapted to eject flame across the surface of the water.

11

12. A device as in claim 1 wherein said stabilized pyrophoric magnesium is carbo-thermic magnesium paste.

13. A device as in claim 1 wherein said stabilized pyrophoric magnesium is in the form of pellets containing coked carbothermic magnesium dust-hydrocarbon mixture.
